CLOSURE DEVICE AND METHOD OF
MAKING SAME

Isadore Lawrence Lesavoy, Allentown, Pa.

Application August 24, 1945, Serial No. 612,373

10 Claims. (Cl. 215—38)

1

This invention relates to caps or covers, fabricated of paper, cardboard, fibre and similar materials, for jars, bottles and other containers. The invention more particularly relates to the skirted type of jar cover having a turned-down skirt or flange encircling the upper portions of the jar contiguous to its mouth.

One of the objects of the invention is to provide a pre-formed cap blank which may be cheaply made, and quickly and economically applied to cover the mouths of jars and other containers. Another object is to provide a skirted jar cover which when applied to the jar, will be held securely in place by the tight-fitting of its skirted portion. An allied object is to provide a jar cover having a peripheral portion which is pre-formed and pre-spotted with adhesive so that when folded over the mouth of the jar it forms a skirt having overlapping portions which are secured together by the adhesive, in a tight-fitting manner to hold the cap firmly in place. This allied object of the invention contemplates a jar cover which is pre-formed and pre-spotted with adhesive so that it can be formed into a tight-fitting skirted type of cap without the need of applying adhesive or moisture to the blank as it is being formed into a tight-fitting cover for the jar or other container.

A further object of the invention is to devise a method of pre-forming jar cap blanks and applying them to jars or other containers to form a tight-fitting skirted type of jar cover. This object further contemplates the step of pre-spotting the blank with adhesive. An allied object is to devise a method of pre-forming jar cap blanks and applying adhesive to certain portions thereof, the preforming of the blank being such that all portions of the blank to which adhesive is required to be applied, will be presented at one side of the blank, so that the adhesive may be more facilely applied to a single side of the blank to coat all portions of the blank required to be pre-spotted with adhesive. A further object is to devise a method of pre-forming jar cap blanks and pre-spotting portions thereof with adhesive, so that the pre-formed and adhesive-coated blanks may be stacked without adhering to each other. An allied object is to provide pre-formed and pre-coated jar cap blanks which may be stacked without adhering to each other.

For the attainment of the foregoing and such other objects as may appear or be pointed out herein, two embodiments of the invention are shown in the accompanying drawings.

2

Referring to the drawings,

Figure 1 is a front view of a jar to which the improved skirted cap has been applied;

Figure 2 is a plan view of a blank in the initial state of pre-forming according to one embodiment of the invention;

Figure 3 is a plan view of the blank of Figure 2 in the latter stages of pre-forming and pre-spotting with adhesive;

10 Figure 4 is an enlarged perspective view of a portion of the improved skirted jar cap according to the first embodiment of the invention;

Figure 5 is a front view of a container having an improved skirted jar cap according to the second embodiment of the invention;

15 Figure 6 is a plan view of a blank in the initial stage of pre-forming according to the second embodiment of Figure 5;

Figure 7 is a plan view of the blank of Figure 8 in the latter stages of pre-forming and pre-coating; and

20 Figure 8 is a perspective view of a jar covered by the improved skirted cap according to the first embodiment (as in Figure 1), a tear being shown in the tympan of the cap.

25 In both forms of the invention a circular blank is employed; the circular blank used in the embodiment of Figures 1-3 is shown in Figure 2 and designated 12; the circular blank employed in the embodiment of Figures 5-7 is shown in Figure 6 and designated 21. Referring first to the embodiment of Figures 1-4, circular blank 12 (Figure 2) is provided with equi-spaced radial cuts 15 extending a short distance inwardly from the periphery of the circular blank; radial cuts 15 thus form a plurality of flaps, designated 14 in Figure 2, around the periphery of the blank. A concentric indicator line 16 enclosing the central portion 13 of the blank may be provided to aid 30 in centering the pre-formed blank over the mouth of the jar or container.

35 Alternate ones of the flaps 14, Figure 2, are folded at their uncut sides to overlie the contiguous portions of the blank, thus forming the serrated blank shown in Figure 3. In the latter figure the unfolded flaps are designated 14 as in Figure 2, while the folded flaps are designated 17. The marginal portions 18 along both radial sides of the unfolded flaps 14 and the marginal portions 19 along both radial sides of the folded flaps 17 are pre-spotted with a coating of adhesive. It will be seen from Figure 3 that, by 40 reason of the folding back of alternate flaps (17), all portions of the pre-formed blank required to 45 be pre-coated with adhesive—namely, marginal

portions 18 and 19—face upwardly, i. e., lie on one side of the pre-formed blank so that the adhesive applicator need operate on only one side of the blank and all the coating operations may be simultaneously performed in a single economical operation.

The adhesive used is of the type which will cause cohesion only between two surfaces which have been coated therewith, i. e., a coated surface will not adhere to an uncoated one. Latex or a solution of para rubber in gasoline have been found suitable for this purpose. By reason of the employment of this type of adhesive and the manner of pre-forming and pre-coating the blanks as shown in Figure 3 so that the adhesive is applied to only one side of the blank, the pre-formed blanks may be stacked without adhering to each other.

In applying the pre-formed and pre-coated blank of Figure 3 to a jar or other container, it is placed over the mouth of the jar with the coated side, Figure 3, upward; the concentric indicator line 16 facilitates centering over the mouth of the jar. The unfolded flaps 14 are then bent downwardly against the sides of the jar to form the foundation for the cap skirt. Then the folded flaps 17 are straightened out and also bent downwardly against the sides of the jar to complete the cap skirt by overlapping the previously bent-downwardly flaps 14, as clearly shown in Figures 1 and 4 where the completed cap is designated 11. In folding or bending down the alternate set of flaps 14, 17, their coated marginal edges, respectively, 18, 19, come into overlapping, bonding contact, thus forming a tight-fitting skirt around the jar.

The circular blank 21, Figure 6, employed in the embodiment of Figures 5-7, differs from the blank 12 of Figure 2 in that the equi-spaced cuts 24 are not radial but are tangent to the small dot-and-dash circle at the center of the blank. As in the blank of Figure 2, blank 21 of Figure 6 has a concentric indicator line 25 enclosing the central portion 22. The tangential cuts 24 form flaps 23 around the periphery of the blank. The corners 26, Figure 6, of each flap 23 is then bent and folded back to form triangular areas 27 (see Figure 7), which overlie contiguous portions of the respective flaps. Adhesive coatings are then applied along the marginal portions 29 of the unfolded edge of the flaps and along the marginal portions 28 of the triangular folded-back corners. The pre-formed and pre-coated blank of Figure 7 is applied to a jar in the manner described above in connection with the blank, Figure 3, of the first form of the invention. The flaps 23 are first turned down against the sides of the jar, and the folded corners 27 are then straightened out to come into overlapping relation to the previously folded flaps 23, to form the completed skirt 20, as shown in Figure 5. The coated marginal portions 29, 28 are thus brought into overlapping, bonding contact to form a tight-fitting skirt about the jar.

In the accompanying drawings, the invention has been shown merely by way of example and in preferred form, but obviously many variations and modifications may be made therein which will still be comprised within its spirit. It is to be understood, therefore, that the invention is not limited to any specific form or embodiment, except insofar as such limitations are specified in the appended claims.

What I claim is:

1. The method of making a skirted type cap

for a container comprising the steps of incising the periphery of a circular blank at spaced points with radially extending cuts to form a plurality of peripheral flaps, folding alternate flaps back to overlie contiguous portions of the blank, applying adhesive to the obverse side of the unfolded flaps along marginal portions of their radial sides and to the reverse side of the folded-back flaps along marginal portions of their radial sides, centering the pre-formed and pre-coated blank over the mouth of the container, turning down the unfolded flaps against the sides of the container, and then straightening and turning down the folded-back flaps against the side of the container in overlapping relation to the flaps first turned down and with their said coated marginal portions in bonding contact.

2. The method of making a skirted type cap for a container comprising the steps of incising the periphery of a circular blank at spaced points with cuts tangential to a circle of less diameter than that of the said circular blank to form a plurality of peripheral flaps, folding a corner of the said flaps back to overlie contiguous portions thereof, applying adhesive to the obverse side of the said folded flaps and to the reverse side of the said folded-back corners, centering the pre-formed and pre-coated blank over the mouth of the container, turning down the unfolded flaps against the sides of the container, and then straightening and turning down the folded-back corners against the side of the container in overlapping relation to the flaps first turned down and with their said coated portions in bonding contact.

3. The method of making a skirted type cap for a container comprising the steps of incising the periphery of a circular blank at spaced points to form a slotted margin, folding back portions of the said slotted margin of the blank, applying adhesive to the obverse side of the unfolded portions of the slotted margin and to the reverse side of the said folded-back portion thereof, centering the pre-formed and pre-coated blank over the mouth of the container, turning down the unfolded marginal portions against the sides of the container, and then straightening and turning down the folded-back portions of the slotted margin against the side of the container in overlapping relation to the portions first turned down and with their said coated surfaces in bonding contact.

4. The method of making a skirted type cap comprising the steps of incising the periphery of a circular blank at spaced points with radially extending cuts to form a plurality of peripheral flaps, folding alternate flaps back to overlie contiguous portions of the blank, applying adhesive to the obverse side of the unfolded flaps along marginal portions of their radial sides and to the reverse side of the folded-back flaps along marginal portions of their radial sides, turning down the unfolded flaps, and then straightening and turning down the folded-back flaps in overlapping relation to the flaps first turned down and with their said coated marginal portions in bonding contact.

5. The method of making a skirted type cap comprising the steps of incising the periphery of a circular blank at spaced points with cuts tangential to a circle of less diameter than that of the said circular blank to form a plurality of peripheral flaps, folding a corner of the said flaps back to overlie contiguous portions thereof, applying adhesive to the obverse side of the un-

folded flaps and to the reverse side of the said folded-back corners, turning down the unfolded flaps and then straightening and turning down the folded-back corners in overlapping relation to the flaps first turned down and with their said coated portions in bonding contact.

6. The method of making a pre-formed and pre-spotted blank for a skirted type cap comprising the steps of incising the periphery of a circular blank at spaced points with radially extending cuts to form a plurality of peripheral flaps, folding alternate flaps back to overlie contiguous portions of the blank, applying adhesive to the obverse side of the unfolded flaps along marginal portions of their radial sides and to the reverse side of the folded-back flaps along marginal portions of their radial sides.

7. The method of making a pre-formed and pre-spotted blank for a skirted type cap comprising the steps of incising the periphery of a circular blank at spaced points with cuts tangential to a circle of less diameter than that of the said circular blank to form a plurality of peripheral flaps, folding a corner of the said flaps back to overlie contiguous portions thereof, applying adhesive to the obverse side of the unfolded flaps and to the reverse side of the folded-back corners.

8. The method of making a pre-formed and pre-spotted blank for a skirted type cap comprising the steps of incising the periphery of a circular blank at spaced points to form a slotted margin, folding back portions of the said slotted margin, applying adhesive to the obverse side of the unfolded portions of the slotted margin and to the reverse side of the said folded-back portions thereof.

9. The method of making a pre-formed and pre-spotted blank for a skirted type cap com-

prising the steps of incising the periphery of a circular blank at spaced points to form a slotted margin, folding back portions of the said slotted margin, and applying adhesive to one face thereof to simultaneously coat parts of the obverse side of the unfolded portions of the slotted margin and of the reverse side of the said folded-back portions thereof.

10. A circular blank for forming into a skirted type cap for containers provided at spaced points about its periphery with radially extending slits, alternate peripheral portions between said slits being folded back to overlie contiguous portions of the blank, presenting a serrated periphery, marginal portions of the obverse side of the unfolded peripheral portions and of the reverse side of the folded-back flaps being coated with a self-cohesive substance, whereby the said blanks may be stacked without adhering to the underside of overlying blanks.
